METHOD FOR CAUSING SPRAYED METAL TO
ADHERE TO METAL SURFACES

Arthur P. Shepard, New York, N. Y., assignor to
Metallizing Engineering Company, Inc., Long
Island City, N. Y., a corporation of New Jersey

Continuation of application Serial No. 366,957,
November 25, 1940, which is a division of applica-
tion Serial No. 221,650, July 27, 1938. This
application April 16, 1940, Serial No. 329,906

3 Claims. (Cl. 29—148)

This invention relates to a new and useful method for causing sprayed metal to adhere to metal surfaces.

In industrial practice a coating of metal is frequently applied to a base of the same or other metal by spraying. For this purpose the metal to be applied is melted and is projected as a spray against the surface to be covered. The application of sprayed metal in this manner may, for example, be carried out to protect the base against corrosion, to provide a surface of the desired ornamental or bearing characteristics, or to build up worn machine parts. In practice adhesion between the base and the sprayed metal is obtained by preliminarily grit-blasting the metal surface. In accordance with my method a higher and more satisfactory adhesion is obtained without resort to grit-blasting.

In carrying out the method of my invention the roughening of a given metal base to be sprayed upon is obtained by running thereon a plurality of circular rows of teeth, the teeth of at least some of said rows being out of line with respect to the teeth of other rows until the desired degree of roughness is obtained. The thusly roughened surface does not show a succession of holes corresponding to the form of the teeth since the teeth do not track or mesh in the surface of the work but, on the contrary, come down at random and in such a way that the surface between the teeth marks first formed is splayed and peaned by subsequent impacts with the teeth to form minute cavities with overhanging outer edges. The base to be sprayed upon is preferably secured in an appropriate metal working machine, such as a lathe or planer, depending upon the geometric form of the base. While the tool containing the circular rows of teeth as, for example, the tool hereinafter described in detail, is secured in the tool holder of the machine and runs upon the surface of the base to be covered.

A suitable instrument that may be utilized in the practice of my method is, for instance, the one described and claimed in my co-pending application, Serial No. 221,650, filed July 27, 1938 (continued as Serial No. 366,957, filed Nov. 25, 1940), of which the instant application is a division.

One illustrative embodiment of an instrument or tool useful in accordance with the invention, as well as certain aspects and embodiments of my invention will be exemplified in the following description read in conjunction with the drawing in which—

Fig. 1 is a cross-section through the tool;

Fig. 2 is a side view of a part of the construction shown in Fig. 1;

Fig. 3 is an enlarged edge view of a part of the construction shown in Fig. 2;

Fig. 4 is a perspective view of a block of metal which has been subjected to the first step of my method;

Fig. 5 is a side view of a cylindrical shape which has been subjected to the first step of my method;

Fig. 6 is a section through the construction shown in Fig. 5 on the plane indicated by 6—6;

Fig. 7 is a section perpendicular to the grooves through part of either the construction shown in Fig. 4 or in Fig. 5;

Fig. 8 is a corresponding section which has received the final step of preparatory treatment in accordance with my invention.

The instrument or tool utilized in the practice of my method comprises (Fig. 1) a group 1 of 20 steel discs carried by spool 2 and held by nut 3 and lock-nut 4 in contact with the spool and with one another. Spool 2 and disc assembly 1 are carried by shaft 5. Spool 2 is secured between shoulder 6 integral with shaft 5 and machine screw 7. By removing screw 7, spool 2 and disc assembly 1 may be removed from the shaft when desired and replaced by a new spool and disc assembly. Shaft 5 is rotatably carried in ball-bearings 10 and 11 mounted in block 12 provided with extension 13. This extension is of such size and proportions that it may be inserted and secured in the ordinary lathe tool post or similarly mounted in the tool holder of a machine tool such as a planer, shaper or boring mill. Alternatively, spool 2 and disc assembly 1 may be similarly carried on a shaft projecting beyond the spool on either side and each end of this shaft may be mounted in a bearing, which bearing is carried by one type of a two-tynes fork forming a tool which may be similarly manipulated by hand or secured in a machine tool post. The construction shown in Fig. 1 has, however, the advantage that if used on work which has a projecting shoulder the disc assembly may be worked closer to the shoulder than the alternative type in which the disc assembly is carried between the tynes of a forked handle.

Each of the discs 8 (Fig. 2) is provided with teeth 9, which teeth in a preferred construction, run about eighteen to the inch. The edges of each tooth define an angle of about 90° from the vertex or point. The teeth of the assembled discs are not in alignment but are staggered with respect to one another. This is illustrated in Fig. 5 in which 15 designates the vertices of the teeth

and 16 the valleys between the teeth of alternate discs, while 17 designates the vertices and 18 the valleys between the teeth of the other discs.

As above pointed out, when using the tool as described in the practice of my invention, it is of advantage to secure the same in the tool holder of a suitable metal working machine and to run the same over the surface of the metal work piece to be treated. Thus, for example, the disc shown in Fig. 4 could be treated in a machine with either a rotary or transitory motion between the tool and the work while the cylindrical shape shown in Figs. 5 and 6 would be best treated in a machine with a rotary motion between the tool and the work.

While in many cases a satisfactory degree of attachment can be obtained by the steps hereinabove described, I have found that a still higher attachment or bond between the sprayed metal and the base is obtained by the additional steps hereinafter described. In accordance with this phase of my invention surface 20 of disc 21 (Fig. 4) has been so treated that a great number of small grooves 26 have been formed therein. In the preferred practice these grooves are approximately $\frac{1}{16}$ " wide and the upstanding teeth or ridges left between the grooves are approximately $\frac{1}{8}$ " wide. In depth the grooves may, for example, range from $\frac{1}{16}$ " to $\frac{1}{8}$ ". The bottoms of the grooves may have any desired contour but in the preferred practice the bottoms 25 (Fig. 7 and Fig. 8) of the grooves 26 are of rounded contour, while the sides 27 of the grooves adjacent the remainder of the original surface are substantially normal to surface 28. Figs. 5 and 6 illustrate a cylindrical shape 28 which has been similarly prepared. In this case the grooves may either be formed as separate circular cuts formed, for example, by the lathe tool, or as one continuous helix formed by cutting a spiral thread in the surface of the cylindrical shape. Since in either case the result is to form a large number of grooves in the surface though in the latter cases the grooves may be the parts of one continuous spiral, this construction may be hereinafter referred to as "forming a number of grooves." After the grooving has been formed, the remainder of the original surface is then operated upon with the tool illustrated in Figs. 1, 2 and 3 until this remainder of the original surface has become roughened to such an extent that the sprayed metal will adhere; preferably, however, the remainder of the original surface has received such treatment by this tool that it is peened over and projects over the original limits of the grooving and this construction is illustrated in Fig. 8. Preferably the width of the original surface between grooves after peaning is approximately equal to the width of the intervening space. When such a surface is sprayed on, the sprayed metal builds up within the grooving to form a

body of sprayed metal which is locked in each groove by the dove-tailing and further adheres to the roughened remainder of the original surface to form a total bond or adhesion approaching the tensile strength of the sprayed metal itself. In so applying the sprayed metal the rounded contour of the bottom 25 of the grooving is of advantage since on the initial application the sprayed metal sticks more readily in the 10 groove than would be the case if the grooving were formed with sharp corners or a flat floor. Where the bottom of the grooving is of rounded contour, moreover, there is a relative absence of bridging of the sprayed metal which would result 15 in cavities.

The foregoing description is for purposes of illustration and not of limitation, and it is therefore my intention that the invention be limited only by the appended claims or their equivalents, 20 wherein I have endeavored to claim broadly all inherent novelty.

I claim:

1. In the process of forming, by metal spraying, an adherent coating of metal on a metal surface the method of preparing such surface 25 which comprises providing a rolling tool having a plurality of circular rows of metal splaying and peening teeth, the teeth of at least some of said rows being out of line with respect to the teeth of other rows, rolling such metal surface with such tool to cut irregularly spaced teeth marks, simulating grit blasted marks, into said surface, continuing the rolling of the thusly cut surface with such tool and cause some of said teeth to mesh with previously cut teeth marks and other teeth to splay and peen out of mesh with previously cut teeth marks to thereby obtain a surface simulating a grit-blasted surface.

2. In the process of forming, by metal spraying, 40 an adherent coating of metal on a metal surface, the method of preparing such surface which comprises providing a rolling tool having a plurality of circular rows of metal splaying and peening teeth, the teeth of at least some of said 45 rows being out of line with respect to the teeth of other rows, forming a multiple number of closely spaced grooves in such metal surface, repetitiously rolling the grooved metal surface 50 with such tool to cut irregularly spaced teeth marks, simulating grit-blasted marks, into said surface intermediate said grooves, continuing the rolling of the thusly cut surface with such tool 55 and cause some of said teeth to mesh with previously cut teeth marks and other teeth to splay and peen out of mesh with previously cut teeth marks to thereby obtain a surface, intermediate said grooves, simulating a grit-blasted surface.

3. The method in accordance with claim 2 in which the bottoms of the said grooves are formed 60 in said base with rounded cross-section.

ARTHUR P. SHEPARD.
